TOY LAUNCHING TRAILER

Eugene B. Laskin, Baltimore, Md.

Application July 30, 1953, Serial No. 26,195

Term of patent 7 years

(Cl. D34—15)

To all whom it may concern:

Be it known that I, Eugene B. Laskin, a citizen of the United States, residing at Baltimore, State of Maryland, have invented a new, original, and ornamental Design for a Toy Launching Trailer, of which the following is a specification, reference being had to the accompanying drawing, forming a part hereof.

Fig. 1 is a side elevational view of a toy launching trailer, showing my new design.

Fig. 2 is a top plan view thereof, and

Fig. 3 is a rear and elevational view.

The tractor and the projectile shown in dotted lines in Figs. 1 and 2 are for illustrative purposes only.

I claim:

The ornamental design for a toy launching trailer, as shown and described.

EUGENE B. LASKIN.
